DESIGN FOR A DESK

Benton L. Fay, St. Joseph, Mich.

Application August 17, 1946, Serial No. 132,606

Term of patent 14 years

(Cl. D33—7)

To all whom it may concern:

Be it known that I, Benton L. Fay, a citizen of the United States, residing at St. Joseph, in the county of Berrien and State of Michigan, have invented a new, original, and ornamental Design for Desk, of which the following is a specification, reference being had to the accompanying drawing, forming part thereof.

The figure is a perspective view of a desk showing my new design, the sides not shown in the drawing being plain flat panels corresponding to the flat side shown in the drawing.

I claim:

The ornamental design for a desk, as shown and described.

BENTON L. FAY.
